UNITED STATES PATENT OFFICE

HENRY J. M. HOWARD, OF WASHINGTON, DISTRICT OF COLUMBIA.

FIRE-PROTECTION APPARATUS.

1,413,275.

Specification of Letters Patent. Patented Apr. 18, 1922.

Application filed November 29, 1920. Serial No. 427,011.

To all whom it may concern:

Be it known that I, HENRY J. M. HOWARD, a citizen of the United States, residing at Washington, in the District of Columbia, 5 have invented certain new and useful Improvements in Fire-Protection Apparatus; and I do hereby declare the following to be a full, clear, and exact description of the same, reference being had to the accompanying drawings, forming part of this 10 specification.

This invention relates to fire protection apparatus, particularly applicable in situations where a series or number of different 15 areas are to be given protection through the interposition of a watchman located at an observation station to which information regarding the conditions pertaining at the distant points is transmitted. In the type 20 of apparatus to which the invention particularly relates, the information transmitted informs the watchman continuously of the condition of the air at each of the several distant points, by maintaining a constant 25 draft of air from each of the distant points to the watch station, and the objects of the invention are to provide an improved apparatus which will be practically infallible or, in case of disarrangement, will immediately 30 give notice of the fact and afford means whereby corrective measures may be taken to overcome any difficulty in operation.

The particular apparatus adopted for illustrative purposes is one designed for the 35 protection of a building having a large number of apartments with a watch station located in the basement, the apparatus embodying a conduit leading from each apartment to the watch station with competent 40 means for maintaining a constant draft from each apartment to the station and for indicating the presence of products of combustion, for example, in any apartment, and 45 for indicating any failure of the flow of air from any apartment to the station, with means whereby, upon the indication of failure through stoppage of the conduit, for example, a reverse throw of air may be set 50 up in that particular conduit so as to clear the same for subsequent operation.

Referring to the accompanying drawings.—

Figure 1 is a sectional elevation of a 55 building embodying a large number of apartments with a watch station indicated

in the basement, the illustration necessarily being diagrammatic in character.

Fig. 2 is a detail sectional elevation of the indicating and observation chamber at 60 the watch station.

Fig. 3 is a sectional elevation from a point of view at the left of Fig. 2; and

Fig. 4 is a detail showing the discharge end of one of the conduits with a flow indicator associated therewith.

The series of distant points to be protected and which are indicated in the illustration as apartments obviously may be separated from each other and are not necessarily living 70 apartments or areas designed for habitation, but may be storage apartments or even piles of goods or commodities in or in proximity to which the intake ends of the conduits are located. The illustration, however, is typi- 75 cal, and in this illustration the building A is divided into a series of apartments B and from about the center of the ceiling of each apartment a conduit C leads down to the watch station D, which may, for convenience, be located in the basement of the building. The intake end of each conduit is located at a point where it will be most likely to receive any vitiated air or products of combustion, and the exit or discharge ends 85 of all the conduits are preferably grouped together and located in a suction chamber E, preferably having a transparent front wall or door E'. Each of the conduits preferably has its discharge opening so arranged as to 90 direct the draft coming through the same forwardly and directly against the inner face of the transparent wall E'. For convenience, in indicating conditions in the several apartments, the discharge ends of the 95 conduits are separated somewhat so as to blow against different portions of the area of the transparent or glass wall and, hence, air coming through said conduits and impinging on said glass will at once give an 100 indication of conditions pertaining in the apartment. This may be supplemented by observation by the watchman of the condition of the air itself as it issues from the conduit.

In addition, each conduit is provided with 105 what may be conveniently termed a "flow indicator," and while this may take any one of many varied forms which will at once occur to those skilled in the art, a convenient form consists of a very light flap F which 110 is hinged at the upper edge above the conduit opening and is adapted to be blown out

into horizontal or slightly inclined position by the air issuing from the conduit. To prevent the flap or indicator from sticking against the mouth of the conduit, it may be 5 normally held away from the same a slight distance by a stop pin or shoulder *f*, but when no air is passing through the conduit, it will hang down in substantially vertical position. As the result of this arrangement, 10 it will be seen at once, upon inspection of Fig. 2, that, should any one of the indicators fail to stand out in a substantially horizontal or inclined position, that fact will be apparent at once (see, for example, the middle indicator at the bottom row), and the watchman 15 will, therefore, know that the conduit is failing to function and will take corrective measures, as will be presently explained. Each conduit, of course, may be numbered, 20 as shown, to correspond to the number of the apartment or point to be protected, and should there be an indication of fire or smoke in any one of the apartments, the watchman will at once proceed to investigate and take 25 the necessary steps for extinguishing the fire or correcting the undesirable conditions pertaining.

In order to maintain a uniform and steady draft through each and all of the conduits, 30 the suction chamber *E* is connected with an exhaust pump, such as *G*, and the discharge end of this exhaust pump is provided with a valve or shut off *H*, and on the pump side of the valve or shut off there is provided a flexible 35 hose connection *I* and a nozzle *K* which is adapted to be inserted in the discharge end of any one of the conduits. With this arrangement a reverse flow may be set up in any one of the conduits so as to blow out any 40 obstacles such as dust, etc., which may accumulate therein and thereby restore the conduit to its operative condition.

Inasmuch as the frictional resistance to the passage of air through the conduits may 45 be somewhat influenced by the length of the conduit, it becomes desirable to provide some means whereby the flow may be made uniform in all of the conduits in order that the pump capacity may be reduced as far as possible, and while this end may be accomplished by varying the size of the conduits or the inlet openings thereof, it can also be 50 accomplished by providing in each of the conduits a valve such, for example, as indicated at *M*, which may be set through any suitable instrumentality when the apparatus is installed, but which is preferably so arranged that it cannot be subsequently tampered with so as to interfere with the functioning of the apparatus, and to this end the 55 valve may be located behind a removable screen or board which is indicated at *N*, in Fig. 3.

What is claimed is:

65 1. In fire protection apparatus, the com-

bination with a plurality of conduits open at one end to the areas to be protected, a distant observation compartment into which said conduits open, means for withdrawing air from the compartment to induce a flow 70 of air, gas or smoke through the conduits into the compartment, and a flow indicator for indicating when such flow is interrupted or reversed.

2. In fire protection apparatus, the combination with a plurality of conduits open at one end to the area to be protected, a distant observation compartment into which said conduits open, means for withdrawing air from the compartment to induce a flow 75 80 of air, gas or smoke through the conduits into the compartment, means for indicating the presence of products of combustion in the flow from each conduit, and means for indicating when such flow is interrupted or 85 reversed.

3. In fire protection apparatus, the combination with a plurality of conduits open at one end to the areas to be protected, a distant suction chamber or compartment 90 95 into which the opposite ends of said conduits open, said suction chamber having a transparent observation wall, means for withdrawing air from said chamber to induce a constant draft of air through each 95 of the conduits and a flow indicator for each conduit whereby interruption or reversal of flow in any conduit may be observed.

4. In fire protection apparatus, the combination with a plurality of conduits open at one end to the areas to be protected, a distant observation and suction chamber or compartment into which the opposite ends of said conduits open, a transparent wall in 100 said compartment against which the exit openings of said conduit direct the air issuing therefrom, means for withdrawing the air from said compartment or chamber to induce a constant draft through each 105 of said conduits, and a flow indicator in said compartment at the exit end of each conduit.

5. In fire protection apparatus, the combination with a plurality of conduits open 110 at one end to the areas to be protected, a distant suction compartment or chamber into which said conduits open with means for withdrawing the air from said suction compartment or chamber, and an independent air flow indicator at the exit end of each conduit whereby failure of air to flow through any conduit will be indicated.

6. In fire protection apparatus, the combination with a plurality of conduits open 115 120 125 at one end to the areas to be protected, a distant observation and suction chamber or compartment into which said conduits open, a suction pump communicating with said chamber or compartment for drawing 130

air through said conduits, and means for directing at will the discharge from the pump into any individual conduit for reversing the direction of flow therein to clear the conduit of obstructions.

7. In fire protection apparatus, the combination with a plurality of conduits open at one end to the areas to be protected, a distant suction compartment or chamber

into which said conduits open, with means for withdrawing the air from said suction compartment or chamber to induce a flow of air from the areas to be protected into and out of said chamber, and means for regulating the volume of air withdrawn from each conduit whereby the flow may be made uniform in all conduits.

HENRY J. M. HOWARD.
